UNITED STATES PATENT OFFICE.

HERMAN WESLE AND HENRY WESLE, OF MEDFORD, WISCONSIN.

WHEEL.

SPECIFICATION forming part of Letters Patent No. 393,133, dated November 20, 1888.

Application filed February 14, 1888. Serial No. 264,013. (No model.)

To all whom it may concern:

Be it known that we, HERMAN WESLE and HENRY WESLE, both of Medford, in the county of Taylor and State of Wisconsin, have invented 5 a new and Improved Wagon-Wheel, of which the following is a specification, reference being had to the annexed drawings, forming a part thereof, in which—

Figure 1 is a diametrical section of our improved wagon-wheel. Fig. 2 is a side elevation, partly in section, of a portion of the wheel-rim and spokes. Fig. 3 is a side elevation of the two halves of the hub, and Fig. 4 is a transverse section taken on line $x-x$ in Fig. 1.

15 Similar letters of reference indicate corresponding parts in all the views.

The object of our invention is to construct a wheel entirely of iron or steel and to arrange the various parts of the wheel so that they 20 may be readily tightened when worn or accidentally loosened.

Our invention consists in a wagon-wheel formed of a metallic hub in two sections, each provided with arms, which alternate with 25 the arms of the other section forming adjustable mortises for receiving the sockets of the spokes, spokes formed of steel or iron tubes and provided with sockets at opposite ends, the sockets at the inner end being received in 30 the hub and the sockets of the outer end being adapted to receive the rim or tire, and a rim or tire provided with an internal flange for receiving the grooved ends of the spokes, all as hereinafter more fully described.

35 The axle-box A, fitted to the axle B, is tapered externally to receive the parts a b of the hub C. The smaller end of the axle-box A is threaded externally to receive the collar D, by which the hub is held upon the axle-box. The 40 part a of the hub is provided with a sand-rim, e , with the arms d projecting from the flange e parallel with the axis of the hub and separated by intermediate spaces f . Upon the flange e are formed apertured ears g for receiving the 45 bolts h , by which the halves of the hub are fastened together. The part b of the hub differs in construction from the part a only in having the outer end i reduced in diameter to correspond in size with the collar D, the said 50 part b being provided with the flange e' , the arms d' , and the intermediate spaces f' . It is

also provided with apertured ears g' for receiving the bolts h . The arms d of the part a of the hub are adapted to fit in between the arms d' of the part b of the hub. This arrangement of the two halves provides mortises in the spaces f f' between the arms d d' , which are adjustable by the lengthwise expansion and contraction of the hub. To the mortises thus formed are fitted the sockets E, which are 60 bored and internally threaded to receive the spokes F. The said sockets are also provided with studs j , which enter the bore of the spokes F. The outer extremities of the spokes are externally threaded to receive the internally-threaded sockets G, which are provided with studs k , fitted to the bore of the spokes. Each socket G is provided with a transverse groove, l , in its outer end and with a lug, m , in the middle of the groove. To the spokes thus 65 arranged is fitted the rim H, which consists of a band of iron a little thicker than the tire commonly used, furnished with a central flange, n , provided with notches o for receiving the lugs m of the sockets G. By screwing up the 70 bolts h the sockets E are clamped firmly in the hub, the two parts of the hub being firmly drawn together upon the sockets E. The ends of the spokes F are provided with oppositely-arranged threads, one being right hand and 75 the other left, so that by turning the spokes 80 the grooved sockets G may be pressed up against the tire or rim H.

A wheel of this kind having no wood in its construction is not subject to shrinkage or decay, and may at any time be adjusted if the parts become loosened by accident or wear.

Having thus described our invention, we claim as new and desire to secure by Letters Patent—

1. In a vehicle-wheel, the combination of the hub-sections a b , provided with the arms d d' and the flanges e e' , having apertured ears g g' , and the bolts h , passing through the apertures of the said ears, substantially as herein shown 95 and described.

2. In a vehicle-wheel, the combination of a hub formed of the parts a b , adapted to receive the axle-box and provided with arms d d' , the sockets E, clamped in the spaces between 100 the arms d d' , the spokes F, received in the sockets E, the sockets G, attached to the outer

end of the spokes F, and the rim H, adapted to receive the sockets G, substantially as described.

3. In a vehicle-wheel, the combination of a hub formed of the screw-threaded tapering axle-box A, the collar D, the parts *a b*, fitted to the axle-box and provided with arms *d d'*, the sockets E, clamped in the spaces between the arms *d d'*, the spokes F, received in the 10 sockets E E, the sockets G, attached to the outer ends of the spokes F, and the rim H, adapted to receive the sockets G, substantially as specified.

4. The combination of spoke-sockets E G,

threaded internally and provided with the 15 studs *j k*, with the externally-threaded axially-bored spokes F, substantially as specified.

5. The combination, with a series of spokes, F, provided at their outer ends with grooved sockets G, having the lugs *m*, of the rim or tire 20 H, having the internal central flange, *n*, provided with notches *o*, substantially as specified.

HERMAN WESLE.
HENRY WESLE.
